UNITED STATES PATENT OFFICE.

CHARLES G. JOHANNESMEYER, OF GLENDALE, OHIO, ASSIGNOR TO THE LIBERTY MACHINE TOOL COMPANY, OF HAMILTON, OHIO, A CORPORATION OF OHIO.

METAL-PLANING MACHINE.

Application filed July 20, 1925. Serial No. 44,769.

My invention relates particularly to mechanism for controlling the movement of and clamping the cross rail relative to the housings.

Heretofore it has been customary to utilize 5 rotatable screws, in combination with other suitable mechanism, for the purpose of elevating and lowering the cross rail relative to the housings. It also has been customary to 10 provide a manually operative hand lever having operative connection with said mechanism, and to provide another manually operative hand lever having operative connection 15 with clamping mechanism for locking and unlocking the cross rail relative to the housings. If by accident or mistake, the lever for elevating and lowering the cross rail is operated, previous to unclamping the cross rail from the housings, considerable damage is 20 occasioned the machine. Furthermore, the use of rotatable screws necessitates placing considerable mechanism upon the top of the housings, in which position it is inaccessible 25 for convenient oiling, repairing, cleaning and inspection, as well as causing added expenses to the assembly and disassembly costs of the machine.

The objects of my invention are to provide 30 simple, practical and efficient mechanism having a single manually operative lever adapted to automatically unclamp the cross rail relative to the housings previous to forming 35 mechanical operative connection with the actuating driving mechanism for elevating and lowering the cross rail; to provide means adapted to permit a convenient and highly desirable arrangement and location of said 40 manually operative lever and the manually operative control of the driving mechanism; to provide a convenient and easily accessible 45 location of said driving mechanism and to greatly simplify the machine and thereby effect considerable saving of the operator's time, as well as reducing the manufacturing cost of the machine.

My invention consists in providing a suitable shaft having spaced apart rotatable means connected therewith, said means having operative connection with vertical stationary screws rigidly fixed in tensional engagement with the housings of the metal planing machine; in providing, in combination therewith, manually operative means having operative connection with the driving 50 mechanism for rotating said shaft in either

selected direction; in providing said operative means with operative mechanical connection adapted to automatically unclamp the cross rail from said housings previous to forming operative connection with said driving mechanism for elevating and lowering said cross rail and by the use of single manually operative control lever; to provide means whereby operation of said lever uncouples 60 said driving mechanism from said shaft 65 simultaneously with clamping the cross rail to said housing.

My invention further consists in the construction, combination, location and arrangement of parts, as herein set forth and 70 claimed.

In the drawing:

Fig. 1 is a horizontal section taken on a line corresponding to 1—1 in Fig. 2;

Fig. 2 is a front elevation of a cross rail 75 and housings with parts broken away and showing parts in dotted lines;

Fig. 3 is a section taken on a line corresponding to 3—3 in Fig. 2 and showing parts broken away and showing the shaft and integral parts in plan elevation; and 80

Fig. 4 is a section taken on a line corresponding to 4—4 in Fig. 1 and showing the shaft in side elevation and partly broken away. 85

In the preferred construction of my invention I provide stationary vertical screws 1 and 2, respectively, suitably fixed in longitudinal grooves 3 and 4, respectively, in housings or supporting uprights 5 and 6 of a 90 usual metal planing machine having cross rail 7 slidably mounted on the housings, as by recesses 8 and 9 in the cross rail, respectively, receiving rails 10 and 11, respectively, of housings 5 and 6. Suitable means 95 are provided for retaining the rails in the recesses as by rails 10 and 11, respectively, having angular faces 12 and 13, respectively, receiving portions 14 and 15 of the cross rail. Retaining members 16 and 17, suitably fixed 100 to the cross rail, respectively, engage shoulders 18 and 19, respectively, of housings 5 and 6 whereby the cross rail is adapted to be elevated and lowered relative to the housings and without the possibility of the cross rail 105 becoming disengaged from the housings.

Tubular driving shaft 20, suitably mounted in bearings 21 in the cross rail, has spaced apart gears 22 and 23 fixed thereto. The gears 22 and 23, respectively, are in mesh 110

with nut gears 24 and 25, respectively, threaded to vertical screws 1 and 2. The nut gears are suitably secured against vertical movement relative to the cross rail. 5 On projecting end 26 of driving shaft 20 is rotatably mounted driven gear 27 in permanent mesh with and driven by pinion 28 fixed to projecting end 29 of driving shaft 30 of electric motor 31 suitably fixed to the 10 cross rail. Manually operative hand lever 32 has suitable connection with motor 31 whereby the motor, which is connected with suitable outside source of electric supply is adapted to be rotated. The direction of rotation of the motor is controlled by the movement of lever 32 which actuates mechanism well known in the art.

Circular rack 33, mounted on tubular shaft 20, is in mesh with pinion 34 keyed to shaft 35. The pinion is maintained against horizontal movement as by being interposed between bearing 36 and nut 37 which is threaded to end 38 of shaft 35 and screwed in engagement with washer 39 contacting pinion 34. Shaft 35 is rotatably mounted in bearing 36 fixed to web 40 of cross rail 7 by screws 41. The shaft 35 is maintained against horizontal movement by nut 37, (which retains pinion 34 in engagement with end 42 of bearing 36), and integral shaft flange 43 fitted into recess 44 in the bearing. Screw 45 integral with shaft 35 is threaded to nut 46 having rectangular base 47 fitted into rectangular recess 48 in bearing 36, whereby 25 the nut is retained against rotary movement. End 49 of nut 46 is threaded to ball member 50 having rectangular projecting end 51 adapted to be received by a usual wrench for 30 manually screwing the ball member onto the nut. Socket member 52 has concave recess 53 therein and adapted to fittingly receive convex portion 54 of the ball member having its rectangular end 51 projecting through hole 55 in the socket member. Inner ends 56 and 45 57, respectively, of clamping arms 58 and 59 are in engagement with the outer surface of the socket member 52 whereby said socket member is free to rock on the ball member and exert an equalized pressure on ends 56 50 and 57 of the clamping arms. The outer ends 60 and 61, respectively, of clamping arms 58 and 59 are adapted to be forced into frictional engagement with shoulders 62 and 63, respectively, of housings 5 and 6, as by outward movement of socket member 52 acting in unison with arms 58 and 59 pivotally connected to web 40 by fulcrum bolts 64 and 65 threaded to the web. The bolts 64 and 65, respectively, are received in holes 66 and 67, 60 respectively, adjacent the outer edges of clamping arms 58 and 59 whereby the pressure exerted by ends 60 and 61 of the arms is considerably greater than the pressure imparted to ends 56 and 57. The bolts 64 and 65, respectively have heads 68 and 69 in en-

gagement with convex bearings 70 and 71, respectively, having their convex portions fittingly received in concave recesses 72 and 73, respectively, in the outer ends of arms 58, and 59, whereby bearings 10 and 71, respectively, are adapted to slide or rock in recesses 72 and 73 when movement is imparted to the clamping arms. The outer ends 60 and 61, respectively, of clamping arms 58 and 59 are provided with detachably secured convex equalizing strips 74 and 75 adapted to effectively engage shoulders 62 and 63, respectively, of housings 5 and 6, thereby insuring a large surface area of frictional engagement of the arms with the shoulders, and when, after a period of time, the strips are considerably worn, new strips may be substituted therefor, thereby avoiding the necessity of replacing the clamping arms at frequent intervals.

85 Clutch 76 is mounted on projecting end 26 of tubular shaft 20 as by pin 77 extending through longitudinal slots 77', in the tubular shaft, and extending through hole 78' in inner shaft, whereby the tubular shaft is fixed to shaft 78 and whereby the clutch fixed to shaft 78 is adapted to be slid in and out of clutching engagement with teeth 79 integral with driven gear 27.

Manually operative hand lever 80 suitably 95 pivotally mounted in casing 81 has fork 82 received by circumferential groove 83 in clutch 76 whereby the clutch and shaft 78 is adapted to be simultaneously moved horizontally, thereby imparting horizontal motion to circular rack 33 which also is slidably mounted on tubular shaft 20 and fixed to shaft 78 as by pin 84 being received by longitudinal slots at 20' in the tubular shaft. Pin 84 extends through and is fixed to shaft 78, whereby by manual operation of hand lever 80, simultaneously with the movement of clutch 76, is adapted to actuate pinion 34 fixed to shaft 35, thereby locking or unlocking cross rail 7, relative to the housings, depending upon 100 the directional movement of lever 80.

105 The mechanical operations of my invention are as follows:

Assume the mechanism is positioned as shown in Fig. 1 and that lever 32 is positioned 115 so that motor 31 is disconnected from outside source of electric supply.

Hand lever 32 is manually operated for the purpose of imparting the required direction of rotation to motor 31 whereby, through 120 pinion 28, rotary movement is imparted to driven gear 27 rotatably mounted on tubular driving shaft 20. Manually operative hand lever 80 is then operated and clutch 76 (slidably splined to tubular driving shaft 20 by 125 key 77'') is slid into clutching engagement with teeth 79 integral with driven gear 27, whereby previous to the engagement of clutch 76 with clutch teeth 79, circular rack 33 is moved horizontally and being in mesh with 130

pinion 34 causes rotation of shaft 35 having screw 45 integral therewith and threaded to nut 46 threaded to ball member 50, whereby the ball member is caused to move inwardly, 5 thereby releasing the outward pressure of socket member 52 from ends 56 and 57, respectively, of clamping arms 58 and 59 and releasing the frictional engagement of outer ends 60 and 61, respectively, of clamping 10 arms 58 and 59 with shoulders 62 and 63, respectively, of housings 5 and 6. Immediately after the clamping pressure of arms 58 and 59, respectively, with housings 5 and 6 is released, clutch 76 enters meshing engagement 15 with teeth 79 of driving gear 27, and pin 77 imparts rotary movement to shaft 78 and to tubular shaft 20 whereby rotary movement is imparted to gears 22 and 23, fixed to the tubular shaft, and respectively 20 in mesh with nut gears 24 and 25, respectively, threaded to vertical screws 1 and 2. The nut gears are secured against vertical movement relative to the cross rail and thereby impart a vertical directional movement 25 to the cross rail dependent upon the direction of rotation of motor 31. When the cross rail is properly positioned relative to the housings hand lever 80 is manually operated for disengaging clutch 76 from clutch teeth 30 79 of driven gear 27 whereby immediately after disengagement of the clutch from the clutch teeth socket member 52 is forced outwardly in engagement with ends 56 and 57 of clamping arms 58 and 59, thereby clamping 35 the cross rail relative to the housings as by horizontal movement being imparted to circular rack 33 which is in meshing engagement with pinion 34 thereby producing rotation of shaft 35 having integral screw 45 40 threaded to nut 46 threaded to ball member 50 having socket member 52 in operative engagement therewith.

An advantage of my invention is that tubular driving shaft 20 cannot be rotated through manual operation of either hand lever 32 or 80 while arms 58 and 59, respectively, are in clamping engagement with housings 5 and 6. If, when the mechanism is positioned, as shown in Fig. 1, hand lever 32 is actuated for forming electrical connections for rotating motor 31 driven gear 27 merely rotates on tubular shaft 20 without effecting rotation of the tubular shaft or causing damage to the mechanism, in which case, after motor 31 is rotating previous to the engagement of clutch 76 with clutch teeth 79 of the driving gear, it is necessary to manually operate hand lever 80 for forming engagement of the clutch with the clutch teeth and which operation of hand lever 80 automatically unclamps the cross rail from the housings previous to engaging the clutch with the clutch teeth of the driving gear.

Also, when clutch 76 is in meshing engagement with clutch teeth 79 of driven gear 27

and hand lever 80 accidentally is operated for disengaging the clutch from the clutch teeth previous to manual operation of hand lever 32 for stopping rotation of motor 31, the cross rail is clamped to the housings and driven gear 27 is permitted to rotate harmlessly on tubular shaft 20 until hand lever 32 is operated for disconnecting motor 31 from the outside source of electric supply. 70

It is therefore apparent that I have invented a thoroughly practical, efficient and highly desirable device for the purposes intended and which, not only is a safeguard against damage to mechanism caused by wrongful operation of the controlling levers by inefficient operators, but also considerably simplifies the movements of an operator for the reason that heretofore it has been customary to construct metal planing machines with one manually operative hand lever for clamping the cross rail relative to the housings and another manually operative hand lever for engaging the driven mechanism with the cross rail elevating and lowering mechanism. 75 80 85 90

Another advantage of my invention is that the use of the usual rotatable screws necessitates mechanical connections with mechanism positioned on the top of the vertical housings and in which position considerable time is consumed by the operator in gaining accessibility thereto for the purpose of cleaning, oiling and inspecting the mechanism and for making required adjustments. Furthermore, I have provided a combination of mechanism which has a desirable arrangement of the manually operative control levers whereby an operator's time is saved, as well as considerably reducing the manufacturing cost of the machine.

While I have chosen to illustrate the form and construction of my invention by the herein drawings and explanations of the same I desire to emphasize the fact that the form and explanations as relate thereto are not intended to include all of the structures in which my invention may be incorporated. It is, therefore, understood that my invention resides in the combination, arrangement and location of parts and in the details of construction, as hereinafter claimed, and that changes in the precise embodiment of the invention can be made within the scope of what is claimed without departing from the spirit of the invention.

What I claim as new and desire to secure by Letters Patent is:

1. In a metal planing machine having a pair of spaced apart vertical housings, a cross rail slidably mounted thereon, means for elevating and lowering said cross rail on said housings, manually operative means controlling said means, means for clamping said cross rail to said housings and to automatically unclamp it therefrom previous to actua- 130

tion of said cross rail elevating and lowering means, and comprising a driving shaft mounted on said cross rail, a clutch fixed to said shaft and operatively connected with said manually operative means, a circular rack slidably mounted on said shaft and operatively connected with said manually operative means, a pair of fulcrum arms adapted to engage said housings, respectively, and means operatively connecting said arms with said circular rack whereby said arms, respectively, are actuated in clamping engagement with said housings.

2. In a metal planing machine having a pair of spaced apart supporting housings, a cross rail slidably mounted thereon, a tubular driving shaft rotatably connected with said cross rail, a pair of spaced apart gears fixed to said shaft, an inner driving shaft within said tubular shaft, a driving gear rotatably mounted on said tubular shaft and having clutch teeth integral therewith, a clutch slidably mounted on said tubular shaft adjacent said driving gear and secured against rotary movement thereon and fixed to said inner driving shaft, manually operative means adapted to slide said clutch into engagement with said teeth, a circular rack slidably mounted on said tubular shaft and secured against rotation thereon and fixed to said inner driving shaft, a shaft rotatably mounted in said cross rail and retained against longitudinal movement, a pinion gear keyed to said last shaft and in permanent mesh with said rack, a screw integral with said last shaft, a nut threaded to said screw and retained against rotation, a convex member threaded to said nut, a socket rockingly mounted on said convex member, a pair of arms pivotally connected to said cross rail and having their outer ends, respectively, adapted to engage said housings and having inner ends in contacting engagement with said socket member whereby longitudinal movement of said inner shaft is adapted to engage said clutch with said clutch teeth and clamp and unclamp said cross rail relative to said housings and means to elevate and lower said cross rail.

3. In a metal planing machine having a pair of spaced apart housings, a cross rail slidably mounted thereon, a tubular driving shaft rotatably connected with said cross rail, a pair of spaced apart gears fixed to said shaft, an inner shaft within said tubular shaft and secured thereto, a driving gear rotatably mounted on said tubular shaft and having clutch teeth integral therewith, a clutch slidably mounted on said tubular shaft and secured against rotary movement thereon and positioned adjacent said driving gear and fixed to said inner shaft, manually operative means adapted to slide said clutch into engagement with said driving gear clutch teeth, a circular rack slidably mounted on said tubular shaft and secured against rotation thereon and fixed to said inner shaft, a shaft rotatably mounted in said cross rail and retained against longitudinal movement, a pinion keyed to said last shaft and in mesh with said rack, a rotatable screw integral with said last shaft, a nut threaded to said rotatable screw and retained against rotation thereon, a convex member threaded to said nut, a socket rockably mounted on said convex member, a pair of arms pivotally connected with said cross rail and having their outer ends, respectively, adapted to engage said housings and having their inner ends in contacting engagement with said socket member whereby longitudinal movement of said inner shaft is adapted to engage said clutch with said clutch teeth and clamp and unclamp said cross rail relative to said housings, a vertical stationary screw fixed to each of said housings, means connecting said last screws and said first gears whereby rotation of said first gears is adapted to elevate and lower said cross rail and driving means having operative connection with said driving gear and operatively connected with said manually operative means whereby operation of said manually operative means is adapted to unclamp said cross rail relative to said housings previous to meshing said clutch with said clutch teeth, substantially as and for the purposes specified.

3. In a metal planing machine having a pair of spaced apart supporting housings, a cross rail mounted thereon, a tubular driving shaft rotatably connected with said cross rail, an inner driving shaft within said tubu-

lar shaft, a driving gear rotatably mounted on said tubular shaft and having clutch teeth thereon, a clutch slidably mounted on said tubular shaft adjacent said driving gear and secured against rotary movement thereon and fixed to said inner driving shaft, a shaft rotatably mounted in said cross rail and retained against longitudinal movement, a pinion gear keyed to said last shaft and in permanent mesh with said rack, a screw integral with said last shaft, a nut threaded to said screw and retained against rotation, a convex member threaded to said nut, a socket rockingly mounted on said convex member, a pair of arms pivotally connected to said cross rail and having their outer ends, respectively, adapted to engage said housings and having inner ends in contacting engagement with said socket member whereby longitudinal movement of said inner shaft is adapted to engage said clutch with said clutch teeth and clamp and unclamp said cross rail relative to said housings and means to elevate and lower said cross rail.

4. In a metal planing machine having a pair of spaced apart housings, a cross rail slidably mounted thereon, a tubular driving shaft rotatably connected with said cross rail, a pair of spaced apart gears fixed to said shaft, an inner shaft within said tubular shaft and secured thereto, a driving gear rotatably mounted on said tubular shaft and having clutch teeth integral therewith, a clutch slidably mounted on said tubular shaft and secured against rotary movement thereon and positioned adjacent said driving gear and fixed to said inner shaft, manually operative means adapted to slide said clutch into engagement with said driving gear clutch teeth, a circular rack slidably mounted on said tubular shaft and secured against rotation thereon and fixed to said inner shaft, a shaft rotatably mounted in said cross rail and retained against longitudinal movement, a pinion keyed to said last shaft and in mesh with said rack, a rotatable screw integral with said last shaft, a nut threaded to said rotatable screw and retained against rotation thereon, a convex member threaded to said nut, a socket rockably mounted on said convex member, a pair of arms pivotally connected with said cross rail and having their outer ends, respectively, adapted to engage said housings and having their inner ends in contacting engagement with said socket member whereby longitudinal movement of said inner shaft and said rack is adapted to clamp and unclamp said cross rail relative to said housings, a vertical stationary screw fixed to each of said housings, means connected with

said screws and said first gears, respectively, whereby rotation of said first gears is adapted to elevate and lower said cross rail relative to said housings, and means for rotating said 5 driving shaft and operatively connected with said manually operative means whereby operation of said manually operative means is adapted to simultaneously unclamp said cross rail relative to said housings and elevate and 10 lower said cross rail relative to said housings.

5. In a metal planing machine having a pair of spaced apart vertical housings, a cross rail slidably mounted thereon, a tubular driving shaft rotatably mounted in said cross rail, a pair of spaced apart gears fixed to said shaft, an inner shaft slidably mounted within said tubular shaft and secured against rotation relative thereto, a driving 15 gear rotatably mounted on said tubular shaft and having clutch teeth integral therewith, a clutch slidably mounted on said tubular shaft and secured against rotary movement thereon and positioned adjacent said driving gear 20 and secured against rotation relative thereto, a driving gear clutch teeth and fixed to said inner shaft, manually operative means adapted to slide said clutch into engagement with said driving gear clutch teeth, a circular rack slidably mounted on said tubular shaft and secured against rotation thereon and fixed to said inner shaft, a shaft rotatably mounted in said cross rail and retained against longitudinal movement relative to said cross rail, a pinion keyed to said last shaft and in mesh with said rack, a rotatable screw integral with said last shaft, a nut threaded to said rotatable screw and retained against rotation relative thereto, a pair 25 of arms pivotally connected to said cross rail and having their outer ends, respectively, adapted to engage said housings and means connected with said rotatable screw and adapted to engage the inner end of said arms 30 whereby longitudinal movement of said inner shaft is adapted to clamp and unclamp said cross rail relative to said housings, a vertical stationary screw fixed to each of said housings, means connected with said last screws 35 and said first gears, respectively, whereby rotation of said first gears is adapted to elevate and lower said cross rail relative to said housing, driving means mounted on said cross rail and operatively connected with said driving gear whereby operation of said manually 40 operative means is adapted to unclamp said cross rail relative to said housings previous to operatively connecting said driving gear for elevating and lowering said cross rail, 45 and a manually operative lever positioned adjacent said manually operative means whereby the directional rotation of said driving means is controlled.

6. In a metal planing machine having a pair of spaced apart vertical housings, a cross rail slidably mounted thereon, a tubular driving shaft rotatably mounted in said cross rail, a pair of spaced apart gears fixed to said shaft, an inner shaft slidably mounted within said tubular shaft and secured against rotation relative thereto, a driving gear rotatably mounted on said tubular shaft and having clutch teeth integral therewith, a clutch slidably mounted on said tubular shaft and secured against rotary movement thereon and positioned adjacent said driving gear and fixed to said inner shaft, operative means adapted to slide said clutch into engagement with said driving gear clutch teeth, a circular rack mounted on said tubular shaft and secured against rotation thereon and fixed to said inner shaft, a pair of arms pivotally connected to said cross rail and having their outer ends, respectively, adapted to engage said 65

cured against rotation relative to said tubular shaft, a driving gear rotatably mounted on said tubular shaft and having clutch teeth integral therewith, a clutch slidably mounted on said tubular shaft and secured against rotary movement thereon and positioned adjacent said driving gear teeth and fixed to said inner shaft, manually operative means adapted to slide said clutch into and out of engagement with said driving gear 70 clutch teeth, a circular rack slidably mounted on said tubular shaft and secured against rotation thereon and fixed to said inner shaft, a shaft rotatably mounted in said cross rail and retained against longitudinal movement relative to said cross rail, a pinion keyed to said last shaft and in mesh with said rack, a rotatable screw integral with said last shaft, a nut threaded to said rotatable screw and retained against rotation relative thereto, a pair 75 of arms pivotally connected to said cross rail and having their outer ends, respectively, adapted to engage said housings and means connected with said rotatable screw and adapted to engage the inner end of said arms 80 whereby longitudinal movement of said inner shaft is adapted to clamp and unclamp said cross rail relative to said housings, a vertical stationary screw fixed to each of said housings, means connected with said last screws 85 and said first gears, respectively, whereby rotation of said first gears is adapted to elevate and lower said cross rail relative to said housing, driving means mounted on said cross rail and operatively connected with said driving gear whereby operation of said manually 90 operative means is adapted to unclamp said cross rail relative to said housings previous to operatively connecting said driving gear for elevating and lowering said cross rail, 95 and a manually operative lever positioned adjacent said manually operative means whereby the directional rotation of said driving means is controlled.

7. In a metal planing machine having a pair of spaced apart housings, a cross rail slidably mounted thereon, a tubular driving shaft rotatably mounted in said cross rail, a pair of spaced apart gears fixed to said shaft, an inner shaft slidably mounted in said tubular shaft and secured against rotation relative thereto, a driving gear rotatably mounted on said tubular shaft and having clutch teeth integral therewith, a clutch slidably mounted on said tubular shaft and secured against rotary movement thereon and positioned adjacent said driving gear and fixed to said inner shaft, operative means adapted to slide said clutch into engagement with said driving gear clutch teeth, a circular rack mounted on said tubular shaft and secured against rotation thereon and fixed to said inner shaft, a pair of arms pivotally connected to said cross rail and having their outer ends, respectively, adapted to engage said 110

115

120

125

130

housings in clamping relation and having means operatively connected with said circular rack and the inner ends of said arms whereby operation of said manually operative means is adapted to clamp and unclamp said cross rail relative to said housings, a vertical screw fixed to each of said housings, a nut threaded to each of said screws and rotatably secured in said cross rail, a gear fixed 10 to each of said nuts and in mesh with said first gears, respectively whereby rotation of said tubular shaft is adapted to elevate and lower said cross rail relative to said housings, driving means operatively connected 15 with said driving gear whereby operation of said manually operative means is adapted to rotate said tubular shaft and said mechanism being arranged so that operation of said manually operative means is adapted to unclamp 20 said cross rail from said housings previous to operatively connecting said driving means

with said tubular shaft for elevating and lowering said rail.

8. In a metal planing machine, a supporting housing, a cross rail slidably mounted thereon, a tubular driving shaft rotatably connected with said cross rail, a plurality of spaced apart gears fixed to said shaft, an inner driving shaft within said tubular shaft, a driven gear rotatably mounted on said tubular shaft and having clutch teeth integral therewith, a clutch slidably mounted on said tubular shaft adjacent said driven gear and secured against rotary movement thereon and fixed to said inner driving shaft, means 35 adapted to slide said clutch into engagement with said teeth, a circular rack fixed to said inner driving shaft and slidably mounted on said tubular shaft, and rail locking means operated by said circular rack.

CHARLES G. JOHANNESMEYER.
